UNITED STATES PATENT OFFICE

CHARLES A. CHAPMAN, OF ESTES PARK, COLORADO

BEVELING, GROOVING, AND CUTTING TOOL

Application filed July 7, 1930. Serial No. 465,938.

This invention relates to improvements in cutting and grooving tools and has reference more particularly to a special tool designed for use in connection with fibrous composition boards of the type known as celotex and similar articles.

It is becoming increasingly prevalent for builders and others to employ, for heat insulating purposes, a fibrous board which is generally made from sugar cane pulp, corn stalks or similar fibrous material, or which is made from wood pulp. These fibrous boards are quite soft and can be readily cut and worked by means of different tools. When boards of the type referred to are used for finishing basement rooms, attics, and in other places where a decorative effect is desired, it is customary to panel the boards by cutting grooves in their surfaces or by beveling their edges so that when they are assembled there will be V-shaped grooves in the line separating the adjacent boards or panels. It is also often desirable to overlap the adjacent edges of the boards in a manner known as shiplap joints where smooth surfaces are desired.

It is the object of this invention to produce a convenient and substantial tool that can be used for cutting and for grooving fibrous boards of the type above referred to and which can be easily set so as to accommodate different sizes of boards so as to make different depths and widths of grooves.

This invention, briefly described, consists of a frame having two parallel side members connected at their ends with transverse members which serve to hold the side members in spaced relation. One of the side members is preferably adjustably secured to the ends of the transverse members so that its distance from the other side member can be varied to suit different conditions. The two side members are provided with supporting lugs to which clamping members are attached. These clamping members are provided with cutting blades and are downwardly and inwardly inclined and the blades are so arranged that when the tool is drawn longitudinally the two blades will cut a V-shaped groove in one side of the material. The tool is also provided with guides that direct its

movement for the purpose of making the grooves parallel with the edges of the board. One of these guide members is provided with a cutting blade that is arranged to split the board inwardly from the edge and when this is employed, one or both of the inclined blades are removed and another blade attached that cuts at right angles to the surface of the board.

Having thus briefly described the invention, the same will now be described in detail, and for this purpose reference will be had to the accompanying drawings in which the preferred embodiment of the invention has been shown, and in which:

Fig. 1 is a top plan view of the tool, showing the same arranged for cutting a V-shaped groove;

Fig. 2 is a section taken on line 2—2, Fig. 1, and shows the tools in position for cutting a V-shaped groove in a board of celotex;

Fig. 3 is a section taken on line 3—3, Fig. 1 and shows the manner in which one of the blade holding clamps is secured to one of the side members;

Fig. 4 is a view looking in the direction of arrow 4 in Fig. 3;

Fig. 5 is a view similar to that shown in Fig. 1, but drawn to a larger scale and with parts broken away, this view shows the tool arranged for cutting a shiplap groove;

Fig. 6 is a section taken on line 6—6, Fig. 5;

Fig. 7 is a view looking in the direction of arrow 7 in Fig. 5, and shows a side elevation of the vertical cutting tool;

Fig. 8 is a view looking in the direction of arrow 8, Fig. 5, a portion of the side member being broken away;

Fig. 9 is a view looking in the direction of arrow 9, Fig. 6, and shows the manner in which the horizontal cutting tool is held in place on the guide; and

Fig. 10 is a view showing the different kind of cuts that can be made by means of this tool.

In the drawing reference numerals 1 and 2 indicate the side members of the frame and numerals 3 and 4 the end members. The end members are connected with side member 1

by means of screws or rivets 5 and are provided at their free ends with slots 6 for the reception of bolts 7 by means of which the side member 2 is secured to the transverse members in the manner shown. Each transverse member is provided with a handle 8 that is grasped by the operator when he uses the tool. For the purpose of guiding the tool, bars 9 have been provided. These bars 10 are secured to the side members 1 and 2 in the manner shown in Fig. 1. Member 2 has two brackets 10 that are held in place by screws or rivets and have upwardly extending portions 11 that are perforated for the 15 reception of bars 9. Secured to the side member 1 are lugs 12 and 13. Lug 12 has a cylindrical portion that is provided with an opening for the reception of one end of one of the bars 9, and lug 13 has a similar cylindrical portion 15 that is provided with an opening for the reception of the corresponding end of the other bar 9. Set screws 14 are provided for holding the bars in place. The other end of lug 13 has a semi-cylindrical 20 portion 15 that is provided on one side with a threaded opening for the reception of the screw 16. This screw is provided with an annular groove 17 on the inside of the head 18. Slidably secured to the outer ends of bars 9 25 is a guide 19. This guide has two hub portions 20 through which the bars 9 extend and these hub portions are provided with set screws 21, by means of which the parts can be clamped in position. When the groove is 30 to be cut some distance from the edge, the guide 19 is employed alone, but if the groove is to be cut close to the edge it is necessary to provide an auxiliary guide bar 22, which is secured to the bars 19 by means of spacing 35 bars 23. These bars have reduced portions 24 that pass through openings in the guide 19 and which have their ends threaded for the reception of clamping nuts 25. The guide bar 22 is so adjusted that it will pass underneath the lower surface of the side member 2 40 in the manner shown in Fig. 2 and the spacing bars 23 are of such length that it can be moved over to a position adjacent the corner of the knife or cutter secured to bar 1, or any 45 position between this and the outer edge of side member 2 and by this means it is possible to cut the groove any distance from the edge of the board 26.

For the purpose of securing the diagonal cutters 27 and 28 in place, each is clamped 50 between two bars 29 and 30. The bars 29 are provided at one end with notches 31 that extend inwardly and at the other end with notches 32 that extend inwardly from one side. The side members 1 and 2 are provided with lugs 33 and 34 whose upper edges are inclined inwardly and downwardly as indicated by reference numeral 35 in Fig. 3. Lugs 34 are provided with stud bolts 36 with 55 which the wing nuts 37 are connected, and

lugs 33 are provided with screws 38 that extend through the slot 31 in the manner shown in the drawing. The lugs 33 and 34 may be secured to the side members in any suitable way, but have been shown as held in place by means of screws 39. By means of the clamping nuts 37 the position of the cutting blades can be adjusted up or down so as to suit any particular requirements and can be clamped in adjusted position by the wing nuts in the manner shown. If it is desired to cut a V-shaped groove like that shown in A in Fig. 10, the parts are adjusted in the manner shown in Figs. 1 and 2. The blades 27 and 28 are so adjusted that each will extend through the plane of the other and in this way the triangular section 40 will be completely severed so as to leave a clean groove.

If it is desired to cut entirely through the board so as to leave a wall at right angles to the surface thereof, the two blades 27 and 28 together with their holders are removed and the cutter assembly shown in Fig. 6 put into place. This assembly consists of a bar 41 that is provided at one end with an inwardly extending notch 42 and has its other end curved downwardly as indicated by reference numeral 43. A clamping plate 44 is held in place by means of two screws 45 and serves to secure the cutting blades 46 and to hold it against movement. On the side of member 41 opposite from that to which the plate 44 is connected, a plate 47 is located. This plate has an opening 48 extending downwardly from the upper end thereof and is secured to member 1 by means of a clamping screw 49 that passes through a slot 50 in the horizontal portion 51. Member 41 has a threaded opening for the reception of a screw 52 which extends through the opening 48 and serves to hold the cutter assembly in place. By means of screw 52, the depth to which the blade 46 can extend into the board can be regulated. The vertical cutter can be used in combination with either one of blades 27 or 28 and in this case a groove like that shown in D, Fig. 10, is cut. The side on which the incline is located is determined by which one of the cutters 27 or 28 is left in place. Where a ship-lap joint like that shown in C Fig. 10, is desired, guide bar 53 is secured to the guide bar 90 in place of bar 22. This bar is held in place by similar means comprising short laterally extending bars 23a that are provided at their outer ends with wing nuts 25a. Bar 53 is provided near its center portion with a notch or cut-out portion 54, within which a clamping plate 55 is located. This plate is held in place by means of screws 56 and serves to hold the cutting blade 57 securely in place. When the parts are adjusted as shown in Figs. 5 and 6, a piece 58 of rectangular cross section is removed, leaving a notch (C, Fig. 10), and if the adjacent edge of the next board is cut in the same manner, the two 130

edges will overlap so as to form a ship-lap joint. If it is desired to make a cut like that indicated in B, Fig. 10, blade 27 is left in place and blade 46 is omitted, and when this is done, the edge of the board will be finished in a manner that will make it resemble D, Fig. 10, when the other board is applied to it.

It will be seen from the above description when read in connection with the drawings that I have produced a simple tool of substantial construction that is so made that different cutter knives can be applied to it in such a manner that grooves of different shapes can be cut at any distance from the edges of the board and which is therefore of great usefulness in preparing celotex and similar fibrous boards when it is desirable to give the wall surfaces a finished appearance.

In Fig. 8 it will be seen that the guide bar 53 is provided at each end with a removable member 59 whose upper end is provided with an inwardly extending lug 60 that overlaps the outer end of side member 2, and which therefore serves to connect the guide to member 2 in such a position that it cannot move downwardly, and therefore the knife 57 will be guided in a straight line during the movement of the tool. I also wish to call attention to the fact that the blades are beveled on one side only and this helps to hold them steady during the cutting operation. The width of the groove that can be cut is controlled by moving the bars 1 and 2 farther away from or closer to each other and this is accomplished by loosening the clamping bolts 7 and moving bar 2 either towards or away from bar 1, after which bolts 7 are tightened and holds the two side members in adjusted position.

When the tool is not in use, it can be disassembled by removing the guides from each other and from the bars 9 and removing the bars 9 from the main body of the tool. The different cutters and cutter clamping devices, can also be removed and placed in separate compartments in a carrying case specially designed for this purpose.

Having described the invention what is claimed as new is:

1. A tool for the purpose described, comprising, a frame having two side members, means for holding them in spaced parallel relation, a blade carried by the frame and extending below the under surface thereof, a second blade carried by the frame, the planes of the two blades intersecting each other in a line parallel with the axis of frame, and a guide bar adjustably secured to the frame.

2. A tool for the purpose described, comprising, a frame having two side members, means for holding them in spaced parallel relation, a blade secured to the inner edge of each side member, the blades being downwardly and inwardly inclined, the planes of the blades intersecting each other in a line

parallel with the side members, the lowermost point of the cutting edge of each blade being below the plane of the other blade whereby intersecting cuts are formed, and a guide bar attached to the frame.

3. A tool for the purpose described, comprising, a frame having two side members, means for holding them in spaced parallel relation, a blade secured to the inner edge of each side member, the blades being downwardly and inwardly inclined, the planes of the blades intersecting each other in a line parallel with the side members, the lowermost point of the cutting edge of each blade being below the plane of the other blade whereby intersecting cuts are formed, a guide bar attached to the frame, and means for adjusting the distance between the side members.

4. A tool for the purpose described, comprising, a frame having two side members, means for holding them in spaced parallel relation, a blade secured to the inner edge of each side member, the blades being downwardly and inwardly inclined, the planes of the blades intersecting each other in a line parallel with the side members, the lowermost point of the cutting edge of each blade being below the plane of the other blade whereby intersecting cuts are formed, a guide bar attached to the frame, means for adjusting the distance between the side members and means for adjusting the guide bar with respect to the frame.

5. A tool for the purpose described, comprising, a frame having two side members, means for holding them in spaced parallel relation, a blade secured to the inner edge of each side member, the blades being downwardly and inwardly inclined, the planes of the blades intersecting each other in a line parallel with the side members, the lowermost point of the cutting edge of each blade being below the plane of the other blade whereby intersecting cuts are formed, a guide bar attached to the frame, and a cutting blade attached to the guide bar, said last named blade lying in a plane parallel with the under surface of the frame.

6. A tool for the purpose described, comprising, a frame having two side members, means for holding them in spaced parallel relation, a blade secured to the inner edge of each side member, the blades being downwardly and inwardly inclined, the planes of the blades intersecting each other in a line parallel with the side members, the lowermost point of the cutting edge of each blade being below the plane of the other blade whereby intersecting cuts are formed, a guide bar attached to the frame, a cutting blade attached to the guide bar, said last named blade lying in a plane parallel with the under surface of the frame and means for slid-

ably interconnecting the ends of the guide bar with the ends of the frame.

7. A tool for the purpose described comprising, a frame having an elongated opening therein, means carried by the frame and located in the opening for cutting a groove when the tool is moved in the direction of its length, two bars secured to the tool and extending laterally therefrom, a guide bar 10 slidably connected with the bars and a second guide bar secured to the first guide bar and adapted to extend underneath the frame.
8. A tool for the purpose described comprising, a frame having an elongated opening therein, means carried by the frame and located in the opening for cutting a groove when the tool is moved in the direction of its length, two bars secured to the tool and extending laterally therefrom, a guide bar 15 slidably connected with the bars, a second guide bar secured to the first guide bar and adapted to extend underneath the frame and means for slidably connecting the ends of the last named guide bar with the ends of the frame.
- 20

9. A tool for the purpose described comprising, a frame having an elongated opening therein, means carried by the frame and located in the opening for cutting a groove 25 when the tool is moved in the direction of its length, two bars secured to the tool and extending laterally therefrom, a guide bar slidably connected with the bars, a second guide bar secured to the first guide bar and adapted 30 to extend underneath the frame, means for slidably connecting the ends of last named guide bar with the ends of the frame and a cutter associated with the last named guide bar, said cutter lying in a plane parallel to 35 the plane of the under surface of the tool.

40 In testimony whereof I affix my signature.
CHARLES A. CHAPMAN.
